(57) **CLAIM**

The ornamental design for a holder for smart device, as shown and described.

DESCRIPTION

FIG. 1 is a perspective view of a holder for smart device showing my new design;

FIG. 2 is a rear perspective view thereof, showing the holder for smart device in an alternate position;

FIG. 3 is a left elevational view thereof, showing the holder for smart device in the FIG. 1 position;

FIG. 4 is a front elevational view thereof;

FIG. 5 is a right elevational view thereof;

FIG. 6 is a rear elevational view thereof;

FIG. 7 is a top plan view thereof; and,

FIG. 8 is bottom plan thereof.

The broken lines depicting a smart device in FIG. 2 represent environmental subject matter which form no part of the claimed design.

1 Claim, 8 Drawing Sheets
